PENCIL

Frederic R. Barker, Georgetown, Mass.

Application July 26, 1933, Serial No. 682,230

24 Claims. (Cl. 120—18)

This invention relates to a writing device of the type having a self-feeding writing element, and its principal object is to provide a pencil wherein, as the writing element or lead wears down to a given readily writable but not easily breakable distance of exposed lead, the feeding mechanism becomes automatically operative to maintain the lead approximately at said distance.

19 Another object of the invention is to provide a mechanism which is of very simple yet readily accessible construction and which is reliable in its automatic operation but is capable of manual operation in case of failure of said automaticity.

Another object of the invention is to allow the use of a special shape of lead which, as the pencil is periodically rolled in the hand while writing, gives a very much finer writing point than leads now in common use.

Further objects of the invention relate to the construction and operation of my pencil and will be apparent from a consideration of the following description and accompanying drawing.

25 In the drawing

Figure 1 is a broken longitudinal section.

Figure 2 is a section on line 2—2 of Figure 1.

Figure 3 is a section on line 3—3 of Figure 1.

Figure 4 is a section on line 4—4 of Figure 1;

30 and

Fig. 5 is a fragmentary longitudinal sectional view showing the relative positions of the control member and writing element during the writing operation.

35 The pencil herein shown for the purpose of illustration comprises an elongate, generally hexagonal body having an outer casing 1 tapered at the lower end to receive the ferrule tip 2. The casing 1 has an axial bore 3 down as far as the beginning of the casing taper. Contiguous with this bore 3 in the casing are the grooves 4 for holding extra leads. Commencing at the bottom end of the bore 3 and running down into the taper of the casing for the distance shown is the

40 smaller bore 5.

Fitting loosely in, and resting on, the bottom of the bore 5 is a tubular runner guide 6 split for its whole length by the slot 7 (Fig. 2). At a distance up equal to the length of the bore 5 45 there is pressed out from this runner guide 6 a lug 8 which fits into one of the grooves 4 and thus keeps the runner guide from turning in the casing 1.

With an easy running fit in this tubular runner 50 guide 6 is the tubular feed screw 9 having a left

hand screw groove. Fitting loosely inside this tubular feed screw 9 is the tubular runner 10 having on it a tit 11 which extends thru the feed screw 9 into the runner guide slot 7. Fitting loosely inside this tubular runner 10 is the tubular lead pusher 12 having on it a tit 13 which extends thru the runner 10 and then on thru the feed screw 9 into the runner guide slot 7 at a distance from the tit 11 (in the position shown) equal to the lead of the screw plus half the width 5 of the feed screw groove, the tits 11 and 13 being of a size approximately half the width of the feed screw groove.

55 Into the upper end of the tubular feed screw 9 is fixedly fitted the tubular check seat 14 the top 15 of which is pressed over to form an outward flange, which abuts a thrust washer 15. With the washer 15 as a seat the spring 16 presses the check 17 against the seat of the check seat 14, the lower end of check 17 being freely guided 20 in said check seat 14. Into an axial hole in the lower end of this check 17 is securely fastened the upper end of the control rod 18 which extends down thru the pencil to a given distance beyond the ferrule 2. Snugly fitted to the outside of this 25 tubular check seat 14 is a short tubular spring seat 19 the top of which abuts the lower side of said flange at top of check seat 14, and the bottom of which is formed with an inward flange which is sprung into a peripheral recess 20 of the 30 runner guide 6. Fastened to this bottom flange of the spring seat 19 is the torsion spring 21 the lower end of which is secured to the lug 8 of the runner guide 6. This spring is not only in torsion but also in a state of compression greater 35 than that of the spring 16 so as to keep the feed screw mechanism pressed up against the thrust washer 15.

40 Firmly holding this thrust washer, and with an easy running fit, fitting over the barrel of the tubular spring seat 19 is the top bearing 22 which is formed with longitudinal depressions as shown (Fig. 3) to allow the passage of the spare leads, and then is flared out to fit firmly over the outside of the hexagon casing 1 (Fig. 1). 45 Fitting over this bearing 22 sufficiently snug to be capable only of manual movement is the eraser barrel 23. This barrel extends up beyond the bearing 22 sufficient to allow to be retained firmly therein an eraser 24 and an eraser thrust seat 50 25. The center of this thrust seat 25 is formed down to fit loosely over the rectangular top of the check 17. (Figs. 1 and 4).

In Figure 1 the runner 10 is shown at the bottom of its stroke in the feed screw 9. Snugly 55

pushed into the lower end of this tubular runner 10 is the short worn down tubular lead 26 ready to be pushed out of the runner 10 by the lead pusher 12 on further manual rotation of the feed screw 9 sufficient to bring the tips 11 and 13 at a distance apart equal to the lead of the feed screw.

From the foregoing construction explanation it will be apparent that the operation of the pencil is as follows:—

The eraser barrel 23 is manually rotated in a left hand direction relative to the casing 1. This causes the eraser seat 24 to rotate the check 17. But the check 17 is frictionally engaged with the check seat 14 by the spring 16 so that said check seat 14 also will rotate. This rotation of the check seat 14 will not only cause to rotate the feed screw 9, to which it is fixed, but will also wind up the spring 21. This left hand rotation of the feed screw 9 relative to the casing 1 and so, on account of the lug 8, also relative to the runner guide 6, will cause the runner 10 and lead pusher 12 to be retracted up into the pencil until they reach the upper end of their stroke. Further rotation of the eraser barrel in this direction simply causes the check 17 to rotate on the check seat 14. In this top position of the runner 10 a full length of a suitable writing element such as a tubular lead 26, or the like elongate piece of graphitic material having a longitudinally extending channel or bore in which the control rod 18 may be received, may be inserted to engage the lower end of runner 10 against the lead pusher 12. The writing end of the lead there protrudes from the ferrule 2 at a distance approximately flush or conterminous with the lower end of the control rod 18. The pencil is then ready for writing.

As, while writing, the lead wears down, the end of the control rod 18 is exposed to the writing pressure at the same time as the lead. This writing pressure against the control rod causes it to lift the check 17 from the seat 14 a very slight amount, sufficient only to cause the check 45 and seat to lose their frictional engagement or grip, and thus allow the seat and the feed screw 9 to which it is fixed, to rotate in a right hand direction under the torsion force of the spring 21. This rotation of the feed screw 9 causes the runner 10 and lead pusher 12 to move down and feed down the lead. When the lead has moved down sufficient to remove the writing pressure from the end of the control rod the check 17 returns to frictional engagement with the check seat 14 55 and so stops the action of the said feed of the lead. This feed of the lead is only a few thousandths of an inch at a time. It will be noticed that the writing point of the lead is exposed to approximately the same distance ready for writing at all times and that the feed control does not impair or interfere with this writing point at any time, as shown more clearly in Fig. 5.

Now to draw attention to the writing point of the lead please observe the following feature. The lead is tubular so that, since the pencil is always held at an angle, as shown in Fig. 5, wear on the side of this tubular lead forms two sharp edges of a width equal to the thickness of the wall of the tube at the points of junction of the plane of the angle of wear and the plane of the end of the tubular lead. Either of these sharp edges may be continually used by rolling the pencil in the hand either one way or the other. It is partly due to this same fact that 75 the pencil is always held at an angle while writ-

ing that the minute action of the feed is so smooth as not to be felt because the touch of pressure on the control tip comes after, as it were, the pressure on the side of the lead.

While I have shown and described one desirable embodiment of the present invention, it is understood that this disclosure is for the purpose of illustration only, and that various changes in shape, proportion, and arrangement of parts, as well as the substitution of equivalent elements 10 for those herein shown and described, may be made without departing from the spirit and scope of the invention, as set forth in the following claims.

I hereby make the following claims:—

1. A writing device of the class described comprising a tubular body tapered at one end, a slotted guide within said body, a feed screw within said guide, a slidable pusher within said screw having offset portions engaging the thread of 20 said screw and the slot of said guide, means urging said screw to rotate relative to said guide whereby to feed said pusher, a control element extending to a given point beyond the tapered end of said body, and means co-operating with 25 said control element to control thereby the amount of relative rotation of said feed screw with respect to said guide.

2. A writing device of the class described comprising a tubular body tapered at one end, a slotted guide within said body, a feed screw within said guide, a slidable pusher within said screw having offset portions engaging the thread of said screw and the slot of said guide, a torsion spring urging said feed screw to rotate relative to said 30 guide whereby to feed said pusher toward tapered end of said body, a control element extending to a given point beyond the tapered end of said body, and means co-operating with said control element to control thereby the action of said 35 spring in rotating the feed screw relative to said guide.

3. A writing device of the class described comprising a tubular body tapered at one end, a slotted guide within said body, a feed screw within 45 said guide, a slidable tubular pusher within said screw having offset portions engaging the thread of said screw and slot of said guide, and a torsion spring acting to urge said screw to rotate relative to said guide whereby to feed said pusher 50 toward tapered end of said body, an axial control element within said pusher but extending to a given point beyond the tapered end of said body, and means cooperating with said control element to control thereby said action of said 55 spring.

4. A writing device of the class described comprising a tubular body tapered at one end and having therein a writing element or lead having a thru axial hole, a longitudinally slotted tubular guide axially fixed in said body, a tubular feed screw rotatably disposed within said tubular guide, a tubular pusher slidably disposed in said tubular feed screw and engaging the inward end of said lead and having offset portions engaging 60 the thread of said screw and the slot of said guide, a torsion spring having one end attached to said guide and its other end connected with the top of said screw acting thus to urge said screw to rotate relative to said guide to actuate 65 the pusher to push out said lead, an axial control element slidably disposed within said axial hole of said lead and having its lower end at a given distance beyond said tapered end of said body and its upper end urged into frictional 70 75

engagement with top of said screw by a compression spring depending from top of said body, a manually rotatable cap fitting over top of said body in slideable but non-rotatable connection with upper end of said control element.

5. A pencil comprising a tubular body having a writing element projecting from one end thereof, mechanism within said body for feeding said writing element outwardly, and control means 10 associated with said mechanism for maintaining the end of said writing element at a predetermined distance beyond the end of said body, said control means including a member having an end conterminous with and disposed within 15 the confines of the end of said writing element and arranged constantly to engage the writing surface as the writing progresses.

6. A pencil comprising a tubular body having a writing element projecting from one end thereof, mechanism within said body for feeding said writing element outwardly, and control means operative to effect the actuation of said mechanism so as to maintain the end of said writing element at a predetermined distance 20 beyond the end of said body, said control means including a member having an end conterminous with and disposed within the confines of the end of said writing element and arranged constantly to engage the writing surface as the writing 25 progresses.

7. A pencil comprising a tubular body having a writing element projecting from one end thereof, mechanism within said body for feeding said writing element outwardly, and control 30 means associated with said mechanism, including a member which projects outwardly beyond said body with its end conterminous with and disposed within the confines of the end of said writing element and arranged constantly to engage the writing surface as the writing 35 progresses, said control means being operative to effect the actuation of said mechanism so as to maintain the end of said writing element at a predetermined distance beyond the end of said 40 body.

8. A pencil comprising a tubular body having a writing element projecting from one end thereof, mechanism within said body for feeding said writing element outwardly, and control 45 means including a member having an end conterminous with and disposed within the confines of the end of said writing element and arranged constantly to engage the writing surface as the writing progresses, said control means being operative in response to the wearing away of said writing element to effect the actuation of said mechanism so as to maintain the end of said writing element at a predetermined 50 distance beyond the end of said body.

60 9. A pencil comprising a tubular body having a writing element projecting from one end thereof, mechanism within said body for feeding said writing element outwardly, and control means comprising an outwardly projecting part conterminous with and disposed within the confines of the end of said writing element and arranged 55 constantly to engage the writing surface as the writing progresses, said control means being operative in response to pressure applied to the end of said projecting part to effect the actuation of said mechanism so as to maintain the end of said writing element at a predetermined 60 distance beyond the end of said body.

70 10. A pencil comprising a tubular body having a lead projecting from one end thereof, said lead

having a longitudinally extending channel, mechanism within said body for feeding said lead outwardly, and means associated with said mechanism comprising a control member disposed in said channel and operative to effect the 5 actuation of said mechanism so as to maintain the end of said lead at a predetermined distance beyond the end of said body.

11. A pencil comprising a tubular body having a lead projecting from one end thereof, said lead having a longitudinally extending channel, mechanism within said body for feeding said lead outwardly, and control means for maintaining the end of said lead at a predetermined distance beyond the end of said body, said means 10 comprising a member disposed in said channel and normally projecting beyond the end of said body with its end conterminous with the end of said lead, said member being operative to effect the actuation of said mechanism in response to the wearing away of the end of the lead.

12. A pencil comprising a tubular body having a lead projecting from one end thereof, said lead having a longitudinally extending channel, mechanism within said body for feeding said lead outwardly, and control means operative in response to the wearing away of said lead to effect the actuation of said mechanism so as to maintain the end of said lead at a predetermined 25 distance beyond the end of said body, said means comprising an elongate member associated with said mechanism, said member being disposed in said channel and projecting beyond the end of said body with its end conterminous with the 30 point of the lead.

13. A pencil comprising a tubular body having a lead projecting from one end thereof, said lead having a longitudinally extending channel, mechanism within said body for feeding said lead 40 outwardly, and control means for maintaining the end of said lead at a predetermined distance beyond the end of said body, said means comprising a member disposed in said channel with its end conterminous with the end of said lead, 45 said member being operative to effect the actuation of said mechanism in response to pressure applied to its end.

14. In a pencil, the combination with a tubular body having a lead projecting outwardly from one end thereof to permit writing, of mechanism for feeding said lead outwardly, and control means comprising a member projecting outwardly beyond said body with its end conterminous with and disposed within the confines of the end 50 of said lead and arranged constantly to engage the writing surface as the writing progresses, said member being operative to effect the actuation of said mechanism to feed said lead outwardly and maintain its projecting end at a predetermined distance beyond the end of said body.

15. In a pencil, the combination with a tubular body having a lead projecting outwardly from one end thereof to permit writing, said lead having a longitudinally extending channel, of mechanism 55 for feeding said lead outwardly, and control means comprising an elongate member disposed in said channel and extending outwardly beyond said body with its end conterminous with the end of said lead, said member being operative to effect the actuation of said mechanism to feed said lead outwardly and maintain its projecting end at a predetermined distance beyond the end of said body.

16. In a pencil, the combination with a tubular 70

- body having a tubular lead projecting outwardly from one end thereof to permit writing, of mechanism for feeding said lead outwardly, and control means comprising an elongate member disposed within said lead with its end conterminous with the end of said lead, said member being operative to effect the actuation of said mechanism to feed said lead outwardly and maintain its projecting end at a predetermined distance beyond the end of said body.
17. A pencil comprising a tubular body having a tubular lead projecting from one end thereof, mechanism within said body for feeding said lead outwardly, and a control member having a part disposed within said lead with its end conterminous with the end of said lead, said member being operative to control the operation of said mechanism in such a manner as to maintain the end of said lead at a predetermined distance beyond the end of said body.
18. A pencil comprising a tubular body having a tubular lead projecting from one end thereof, mechanism within said body for feeding said lead outwardly, and control means, including a part disposed within the bore of said lead, operative in response to the wearing away of said lead to effect the actuation of said mechanism so as to maintain the end of said lead at a predetermined distance beyond the end of said body.
19. A pencil comprising a tubular body having a lead projecting from one end thereof, mechanism normally tending to feed said lead outwardly, check means normally counteracting the feeding movement of said mechanism, and a control member extending outwardly beyond said body with its end conterminous with and disposed within the confines of the end of said lead, said member being associated with said check means and operative to render said check means ineffective to counteract the feeding movement of said mechanism.
20. A pencil comprising a tubular body having a lead projecting from one end thereof, said lead having a longitudinally extending channel, mechanism normally tending to feed said lead outwardly, check means normally counteracting the feeding movement of said mechanism, and a control member disposed in said channel and extending outwardly beyond said body with its end conterminous with the end of said lead, said member being associated with said check means and operative to render said check means ineffective to counteract the feeding movement of said mechanism.
21. A pencil comprising a tubular body having a lead projecting from one end thereof, mechanism normally tending to feed said lead outwardly, check means normally counteracting the feeding movement of said mechanism, and a control rod disposed within said lead and extending outwardly beyond said body with its end conterminous with the end of said lead, said rod being associated with said check means and operative to render said check means ineffective to counteract the feeding movement of said mechanism.
22. A writing element for use with a pencil of the class described, said writing element comprising an elongate lead having an axial bore extending from one end to the other.
23. A writing element for use with a pencil of the class described, said writing element comprising a cylindrical lead having an axial bore extending from one end to the other.
24. A writing element for use with a pencil of the class described, said writing element comprising a tubular piece of graphitic material.
